[57] CLAIM

The ornamental design for a tire, as shown and de-
scribed.

DESCRIPTION

FIG. 1 is a perspective view of a tire showing our new
design it being understood that the tread pattern is re-
peated uniformly throughout the circumference of the
tire and the opposite side is the same as that shown;
FIG. 2 is a front elevation view thereof; and
FIG. 3 is a side elevation view thereof.

FIG. 1

FIG. 2

FIG. 3
